Application December 28, 1934, Serial No. 759,495

8 Claims. (Cl. 197—4)

This invention relates to means for cryptographically transposing an intelligible sequence of characters forming a message into a different and unintelligible sequence forming a code message, together with means for translating the incoherent and unintelligible sequence of characters into the initial and intended formation of the original message.

The combinations of alphabetical letters into words and sentences having some meanings in the different languages are only a part of the total permutations possible with the number of letters contained in their respective alphabets. Permutations have a very great importance in mathematics and in cryptography.

Crypting is a science by means of which letters, words and sentences are moved from the clear field of coherent understandable permutations and are hidden in the haze of permutations not yet elected to convey human thoughts, emotions and understanding.

De-crypting is an art by means of which the incoherent suite of letters of the cryptic message are translated into its clear intended meaning. The time taken by the art to de-crypt any cryptic message is the coefficient of resistance of the message. All cryptic messages can be de-ciphered since it is only a question of time, which is the essence required to be successful in the particular translation.

Any method of crypting involves a number of tedious operations which can be accomplished by mechanical applicances. As the art has no definite mathematical base to work upon, but depends on information, knowledge, intuition and their respective correlation, any crypting machine to be of any practical value has to be conceived in such a manner as to reduce the order of repetition of letters in various languages to absolutely a minimum.

The present invention is based on permutations, and as clear, intelligible writing in any language is by nature nothing but permutations of letters, it is necessary, first of all to select our particular field, to adopt a cryptic alphabet, such as represented by the key board of the average typewriter, or any other that may be desired. Since the mechanism, when in action, constantly shifts letters from the clear to the cryptic field, it is also necessary to establish a starting letter of the message and its relative position to the printing mechanism; the starting letter of the key board; the relative position of the "incoherer" to the printing wheel; the direction in which the messages are crypted and de-crypted;

the various alphabets placed in the dial; the particular sequence of the letters of the alphabet inserted in the printing mechanism.

This outline of variables or number of keys, just set forth, is sufficient to off-set the "law of repetition" of letters in various languages, it includes the whole permutation field given by the alphabets of any language, and also includes the substitution of letters, transposition of ciphers, and superimposition of alphabets.

An object therefor of the present invention is to provide means by which the transposition of characters is continuously variable, in contradistinction to known devices in which transpositions are effected in an orderly and predetermined movement.

Another object of the present invention is to provide means for varying the operation of the device according to the sequence of characters in the message to be enciphered or deciphered.

A further object is to provide means for automatically and continuously varying the cycles of operation of the device without attention on the part of the operator.

Various other objects and advantages of my invention will be obvious from the following particular description of one form of mechanism embodying the invention or from an inspection of the accompanying drawings; and the invention also constitutes certain new and novel features of the construction and combination of parts hereinafter set forth and claimed.

In the drawings:

Fig. 1 is a sectional view of the device along the lines 1—1 of Fig. 2.

Fig. 2 is a plan view of the device.

Fig. 3 is another sectional view of the device showing the actuator and shifter mechanism.

Fig. 4 is a plan view through line 4—4 of Fig. 3.

Figs. 5 and 7 detailed views of ratchet wheels.

Figs. 6 and 8 detailed views of "incoherer".

Fig. 9 is an assembly view showing the additional covers opened for operation of the device.

Referring more particularly to the accompanying drawings, a preferred arrangement of the apparatus is shown in Figs. 1, 2, 3 and 4 for coding and de-coding messages. As here shown a part of the apparatus may be mounted in a suitable circular case 1 which is provided with a hinged cover 2. A plurality of indicators or pointers 3, 4 and 5 are shown in a cooperative relationship with the main dial 6. The said pointers are adapted to be positioned separately to select any particular character as viewed from

50
55

the dial 6, and thus form three of the variables or keys in establishing the ensuing permutations.

A brief description of the general operation of the device will now be given in order to render 5 the specific explanation of the construction and operation of the mechanism more comprehensible.

The following preliminary preparations must 10 be complete before actual operation of the cryptograph is attempted. The pointers 3, 4 and 5 are positioned selectively to any desired character 15 in view from the main dial 6, as shown in Fig. 2, the pointers are positioned opposite the characters F, M and X respectively. It must be understood of course, that the sequence of the letters 20 in the alphabet may be varied as desired, that is, separate and different incoherent alphabet discs may be inserted in the main dial 6, reference may be made to Fig. 1 clearly indicating the individual discs which may be employed. Likewise, the printing wheel 13 adapted so as to 25 be displaced by like wheels with the sequence of the characters thereon arranged in a different manner, must be selected and inserted as shown in Fig. 1.

The shifting mechanism 46 must be positioned properly by the control lever 55, as shown in Fig. 2, that is either to its right and left position, which as will be understood, determines the direction 30 of operation of coding and de-coding mechanism.

The paper feed and printing mechanism operated by the actuator 45 is shown in Fig. 9 disposed in an additional cover of the device and 35 shown in its open position maintained whenever the device is in action. In another cover as indicated, character indicating or counting mechanism is shown also operated upon each stroke of the actuator.

40 The physical construction of the cryptograph device is such that in its entirety it can be conveniently operated and held in one hand of the operator which clearly indicates its advantages in the particular field in which it is applicable.

45 Upon completion of the preliminary conditioning of the selective key devices, which of course must be noted for the later de-coding operations, the machine is now ready for preparing the cryptic message. If the message PARIS is desired to be recorded, the knob and stem arrangement 17 controlling pointer 4 is turned so that the pointer is 50 successively positioned to the characters just noted.

55 At the end of each setting for every character the actuator 45 is depressed to record a character. The second character of the message to be recorded is then set up as mentioned and the actuator again is depressed in a similar manner to effect recording another character on the tape. 60 This operation is continued until the complete message is recorded in its cryptic state which may be, KRLAM, depending, of course, upon the key selection, and the automatic operation of the "incoherer" which upon the operation of the 65 actuator displaces the pointer 4 differently for each operation, as will be understood as the description progresses.

70 Let it be assumed now, that this code message is to be de-ciphered. The machine is then conditioned as explained hereinbefore for the transmission of the message, which would be for this example, the setting of pointers 3, 4 and 5 to characters F, M and X, respectively, of a similar alphabet disc. The printing wheel with the similar sequential arrangement of the characters is

used, and finally the shifter control lever is moved to its right position, if the left position as indicated in the Figure 2 was employed for coding the message. The characters KRLAM are then set up individually with the knob and stem arrangement controlling pointer 4 to these individual character designations, and as mentioned hereinbefore, at the end of positioning the pointer to each character the actuator 45 is operated each time to record each of the decoded characters in 16 order to reveal the clear identity of the message, which in this case would be PARIS.

As mentioned hereinbefore the operation of the actuator will cause the pointer 4 to remain in the position selected, or it may be moved to its 15 adjacent character, or to the second or third character depending upon the position of the "incoherer". It is this indefinite operation automatically conducted in conjunction with the other variable key settings which renders this device 20 effective to select an inconceivable number of permutations and combinations and in this manner be successful to hide the clear identity of the message recorded.

In Fig. 1, the pointer 3 is suitably attached to 25 a centrally located arbor 7 having integral therewith at its other extremity a member 8 comprising a cylindrical sleeve section 9 and stud 10 (Fig. 3). Suitably positioned within the cylindrical sleeve are stops 5a urged outwardly by spring 11 30 and maintained in position by collars 12. The printing wheel 13 with character type 14 suitably disposed on its lower surface, is held in position against the member 8 by the stops 5a adapted to yield to the extent that the printing wheel 35 may be removed from the sleeve. The printing wheel is provided with a centrally located opening 15 to permit the insertion of the wheel as explained, and a suitable hole 16 adapted to fit over the stud 10, thereby positioning the wheel rigidly. 40

In addition thereto, the member 8 has a cut-away or notched portion 120 on its periphery opposite the location of stud 10 into which a protruding pin or stud 121 on main wheel 24 is inserted and adapted to actuate or drive the printing wheel in either direction depending on the 45 rotation of the main wheel.

Disposed above the member 8 is a main wheel 24 adapted to be positioned on bearings 65 movable on a circular race support 16, and provided 50 with a plurality of slots 67 equally spaced and equal in number to the characters or letters in the language to be employed. A gear wheel 19 is attached to the main wheel at 68 and is adapted to engage the gear 18 attached to the knob and 55 stem arrangement 17. A bottom lock wheel 21, with equi-distant triangular cuts 22 in its periphery, the number thereof equal to the letters of the alphabet, is disposed above the main wheel 24 and separated therefrom by the ball bearings 26. 60 A lock spring 23 engaging the slots of lock wheel 21 is suitably supported and fastened to the main wheel 24. Ratchet wheels 27 and 28 separated by lock washer 70 are suitably locked or pinned together to the bottom lock wheel 21. The teeth 65 of the ratchet wheels 27 and 28 are pitched in the opposite direction, the purpose of which will be clear as the description progresses. The lock washer 70 is suitably fastened to a sleeve 20 to which the pointer 4 is attached. Pointer 5 is secured to a top lock wheel 35 engaging ball bearings 39 rotating against the top plate 40. Ratchet wheels 41 and 42 with oppositely directed teeth and "incoherer" 29 are all fixed or pinned to the top lock wheel 35 which is provided with a lock 75

spring 36 suitably attached to the top plate 40. The "incoherer" wheel 29 (Figs. 5-8) is provided with a notched cylindrical rim or skirt 31, the latter surrounding and interruptedly covering or 5 straddling the ratchet teeth of wheels 27 and 28 which as will be seen are acted upon by individual pawls, and said rim or skirt is interrupted by irregular openings or notches 32, and the rim portion when between the pawls and corresponding 10 ratchet-wheels prevents the engagement thereof with the ratchet teeth.

The notches or openings are made so as to open up or uncover sometimes one and sometimes two or more of the ratchet teeth of the 15 wheels 27 and 28 as shown in the shaded portions 32a around the wheels. In Figure 8 a development of the "incoherer" illustrates the relative positions of the cuts or openings 32, and that there are two levels of openings, the lower 20 one straddling the bottom ratchet wheel 27 and the upper level the wheel 28, also that the openings are arranged in reverse order in the two levels. The purpose of this arrangement will be evident since it was mentioned that this device is 25 capable of coding and de-coding cryptic messages formed thereby. One level of openings with its correspondingly straddled ratchet wheel is employed for coding the message, and the other level of openings and ratchet wheel are used in 30 conjunction with the de-coding procedure. Due to the arrangement of the super-imposed ratchet wheels in reversed order and the reversed arrangement of the "incoherer" openings, the message formulated in code can be deciphered correctly if the same positioning of the various keys 35 is made before the start of each operation.

Referring now to Figs. 3 and 4, a protruding plunger or actuator 45 is shown connected to a shifter mechanism 46 constructed to embody a 40 plurality of cylindrical sleeves 47 and 48, and to engage a set of supporting springs 49 suitably attached to the casing 1. The sleeves 47, two on each side of the shifter 46, are adapted to support pawls 52 and 53 which engage the lower 45 and upper ratchet wheels respectively. Depending on the position of the shifter mechanism, pawls 52 are in position to act upon ratchet wheels 42 and 27 to rotate the device in one direction, and in a reversed position of the shifter 50 46 the pawls 53 act upon ratchets 41 and 28 to rotate the device in the opposite direction. It is obvious, of course, that the pawls always act in the same direction by virtue of the depression of actuator 45 against the action of the 55 springs 49 to cause the pawls 52 or 53 to engage the adjacent teeth of the corresponding ratchet wheels, and upon release of the actuator the springs restore the shifter 46 and supported pawls to normal position, the said movement of 60 the actuator causing the rotation of the engaged ratchet wheels. A small adjustment comprising an eccentric cam 80 is attached to plate 40 and permits the shifting of the pawls 52 or 53 into engagement with the respective associated ratchet wheels. It has been mentioned hereinbefore 65 that the engagement of pawls 52 with the associated ratchet wheels 27 and 42 operate the mechanism in one direction and the engagement of pawls 53 with wheels 28 and 41 operate the 70 mechanism in the opposite direction. The control lever 55 which can be set in a right or left position as indicated in Fig. 2 is attached to the cam 80 which in turn cooperates with a settable plate 81. The positioning of the pawls 52 and 75 53 is controlled by lever 55 and the said posi-

tioning is effected by the connecting pin 55a attached to plate 81 and to the tube 50 inserted in sleeve 48 of the shifter mechanism 46.

Disposed on the extremities of the tube 50 are wire springs 51 suitably engaging the pawls 5 52 and 53 and as shown in Fig. 4 when the tube and pawl device is positioned to the left the pawls 52 are urged to cooperate with its corresponding ratchet wheels, and when set to the right the pawls 53 are called into action by its springs 10 51 to rotate its corresponding ratchet wheels in an opposite direction, upon depression of the actuator 45 and shifter mechanism 46.

The positioning of the plate 81 by cam 80 also actuates the connector rods 82 to rotate the 15 stop 83 about its pivot 84 so that the stop 83 engages the slots 67 in the main wheel 24, thereby preventing the main wheel from being rotated in a direction opposite to the one permitted by 20 the setting of the control lever 55.

Attached to the arm of actuator 45 is a cam roller 85 adapted upon the depression of the actuator to force a small piston 86 upwardly as viewed in Fig. 3 against the action of an inserted spring 87 and fastened to piston 86 is an 25 arm 88 which has disposed on its extremity a printing hammer 89, and it is obvious upon depression of the actuator 45, the printer hammer is brought into engagement with the type 14 on the printing wheel 13. Referring now to 30 Fig. 9 in an additional cover 90, a suitable paper reel 91 is pivoted about 92 so that the paper 93 can be distributed over the printing hammer 89 when the cover is in open position as shown and returned between a paper feed roller 94 and 35 roller 95 pivoted at 96 and held in this position by spring 97. Integral with roller 94 is a ratchet wheel 98 engaging pawl 110 on an arm 99 bearing a rotatable arm 100 which when the cover 90 is opened can be extended to cooperate 40 with the printing hammer 89 and which is always urged against the said hammer by virtue of a coil spring 101.

Therefore, when the printing hammer 89 is 45 forced upwardly against the type 13, the spring-pressed arm 100 follows the printing hammer to step the pawl 110 ahead to the adjacent tooth on ratchet 98 so that upon the downward movement of hammer 89, arms 100 and 99 of the pawl 110 urges the roller 94 ahead to feed the 50 paper 93 held tightly between rollers 94 and 95. The tape 93 may consist of two thin layers of 55 paper with a double carbon paper between the separate strips of paper to effect printing on both strips of paper when the hammer 89 engages the type 13. The tape strip of paper should be thin enough to permit the impression on its under surface to be seen from the top surface, in this manner effecting two separate 60 records of the message.

Disposed in a top cover 115 is the indicating or counting mechanism 116 of any standard type suitably arranged to be operated by plunger 117 which when the cover is opened is adapted to be actuated by the up stroke of the piston 86 65 (Fig. 3). This indicating mechanism 116 may be convenient to count the number of letters recorded during the coding or decoding of the message and may be attached to the device if so desired.

It has been shown that the three superimposed pointers 3, 4 and 5 are each separately fixed to associated mechanism; pointer 3 is fixed in direct connection with the printing wheel 13 and if the arrangement of the characters on the 75

printing wheel and the alphabet disk are similar, the pointer indicates exactly the position of the selected letter on the printing wheel and clear recording can be effected by the operation of this pointer alone.

The pointer 4 is directly connected to the ratchet wheels 27 and 28 which are disposed inside the "incoherer" by virtue of the fact that the pointer 4 is physically attached to the sleeve 10 20 and the said sleeve is fixedly attached to lock washer 70 interposed between ratchet wheels 27 and 28. It was mentioned hereinbefore that the ratchet wheels 27 and 28 and the lock washer 70 are suitably locked or pinned together to the 15 bottom lock wheel 21. Now, due to the arrangement that pawl 23 is secured to the main wheel 28 and adapted to engage the teeth of the lock wheel 21, the control pointer 4 is impositively connected to the main wheel 24 and printing 20 wheel 14. The pointer 4 is also connected to the knob and stem arrangement 17 by means of the gears 18 and 19 so that by positioning pointer 4 by means of the knob and stem arrangement to a selected character on the disk, the printing 25 wheel is positioned, not necessarily so as to record the same character selected by the pointer 4, but any other character depending upon the original preliminary setup and the automatic operation of the "incoherer"; pointer 5 is fixedly connected to ratchet wheels 41 and 42 which control the "incoherer" 29 and by positioning the pointer 5 to any given position it will shift the position of the "incoherer" to control subsequent operations of the coding mechanism and finally the 30 35 positioning of the printing wheel. The positioning of control lever 55 either to the right or left position as indicated in Fig. 2 determines the direction of rotation of the device by selecting the operating pawls 52 or 53.

Movement of the actuator mechanism 45 and 46 causes the pawls 52 and 53 to be displaced, and as mentioned hereinbefore, to engage the adjacent teeth of the associated ratchet wheels. However at certain periods the pawls are prevented 40 45 to engage the teeth of one group of the associated wheels due to the surrounding skirt of the "incoherer" 29. Therefore it is obvious, that by variably positioning the settable pointers 3, 4 and 5 before operating the device, the subsequent operations of the elements controlling the 50 55 positioning of the printing wheel are varied in accordance with the said setting of the pointers.

The pointer 4, as stated, is used to select the characters to be coded, but due to the differential action of the groups of ratchet wheels, the pointer may be moved automatically away from the character setting during the printing operation.

60 Due to the change of the setting of the pointers automatically while the character is recorded, and of course the change of the setting varies depending upon the selection of a particular character, it is obvious that the number of permutations generated due to the selection and transposition of the characters is sufficiently great enough to prevent or offset any repetition of the sequence of characters recorded.

70 It was mentioned hereinbefore, that coding could be effected by operating the device in both directions, that is, by setting the control lever in either right or left position as indicated in Fig. 2. If one position is chosen for coding, the other position must be used for decoding the message, thereby operating the device in re-

verse direction for decoding as compared to the original direction for formulating the cryptic message.

When using the device to decode the message, in addition to setting up the pointers 3, 4 and 5 in accordance with the setting recorded originally for coding the message, and reversing the setting of the control lever 55, the alphabet disk 6a must be positioned in accordance with the coding or decoding operation. Referring to Fig. 2, the disk 6a is shown to have the characters arranged in an incoherent order in one direction; for instance, the characters A, V, F and H as viewed from the dial 6 are set up in a clockwise direction, the same characters are included on the said disk to be read in a counterclockwise direction when the disk is shifted to enable them to be viewed from the dial 6. 10 15

A plurality of superimposed disks 6a, having the alphabet arranged in a different incoherent order on each one, are grouped in the cover 2. It is understood that the disks are interchangeable so that each can be placed as desired to be viewed from the dial 6. Each disk has two extensions 120 to limit the manual movement of the disks between the stops 121 and 122. The uppermost disk as maintained in the manually set position due to the friction exerted thereon by the other disks included in the cover 2. 20 25

The printing wheel 13 is adapted to have the same arrangement of the type characters and upon the operation of the device in a reverse direction the printing wheel is adjusted in accordance with the letter arrangement of the disk 6a due to the cutout section 120 on the member 8. 35

Therefore, for decoding it is seen that the machine is operated in exactly the reverse direction as compared to the coding operation, and since the operations are begun from a similar setup of the various keys, and the automatic action of the "incoherer" in effecting variable displacement of the pointer 4 during the printing operation is the same as during the coding operation, the setup of the characters of the cryptic message individually, will cause the clear and original message to be recorded. 45

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims

What is claimed is as follows:

1. In a device of the character described, comprising a plurality of settable means, a character printing wheel associated with one of said settable means, a plurality of ratchet wheels associated with another of said settable means, a plurality of similar ratchet wheels associated with still another of said settable means, and means cooperating with certain of said plurality of ratchet wheels during the coding operation and during the decoding operation with the others of said plurality of ratchet wheels, to control the characters recorded by said printing wheel so as to vary from the characters selected by one of the said settable means, and the variations of the recorded characters are in accordance with the original setting of said plurality of settable means. 60 65 70 75

2. In a device of the character described, comprising a plurality of settable means, recording means associated with one of said settable means, a group of controlling elements associated with another of said settable means, a second group of similar controlling elements associated with still another of said settable means, and means cooperating with certain of the controlling elements of said groups to control the recording means whereby the characters recorded differ from the characters selected by one of said settable means.

3. The invention set forth in claim 2 wherein the last named means is arranged to automatically vary the selection of the characters recorded upon the successive selection of the same characters by one of said settable means.

4. The invention set forth in claim 2 wherein the original positioning of the plurality of settable means automatically affects the selection of the unintelligible characters recorded upon the selection of a sequence of intelligible characters.

5. The invention set forth in claim 2 comprising additional settable means the operation of which controls and affects the recording of intelligible characters and corresponding to the original characters selected upon the selection 5 of the aforementioned recorded characters by the same said settable means.

6. The invention set forth in claim 2 in which the last mentioned means comprises a cylindrical rim surrounding and interruptedly covering 10 the said second group of controlling elements.

7. The invention set forth in claim 2 comprising a stem arrangement cooperating with one of said settable means to be operated to position the said settable means to select the characters which are to be recorded and represented 15 by different characters.

8. The invention set forth in claim 2 comprising an actuator cooperating with the two said groups of controlling elements to be operated 20 to effect the recording of the said characters.

ALEXANDRE L. DE LIVI.
